UNITED STATES PATENT OFFICE.

ESTELLE C. RANEY, OF COLUMBUS, OHIO, ASSIGNOR TO THE AUTOMATIC RECLOSED CIRCUIT BREAKER COMPANY, OF COLUMBUS, OHIO, A CORPORATION OF OHIO.

CIRCUIT-CONTROLLING MECHANISM.

1,312,454.

Specification of Letters Patent. Patented Aug. 5, 1919.

Application filed April 29, 1915. Serial No. 24,802.

To all whom it may concern:

Be it known that I, ESTELLE C. RANEY, a citizen of the United States of America, residing at Columbus, in the county of 5 Franklin and State of Ohio, have invented certain new and useful Improvements in Circuit-Controlling Mechanism, of which the following is a specification.

My invention relates to circuit controlling mechanism and has to do with the provision of an automatically reclosing circuit breaker that may be readily adjusted after installation to render it properly responsive, either in opening or reclosing, even though the 10 permanent load may be materially altered.

I am the first to appreciate the fact that the adjustments mentioned are highly desirable and, also, that the load conditions under which the breaker is to open and the load 15 conditions under which the breaker is to close must be met by adjusting means that are relatively independent, since opening and reclosing must occur under widely different conditions.

Thus, the present invention contemplates the use of a means for adjusting the opening point of a breaker and a means for adjusting the reclosing point of such breaker, such means being independently regulable.

Other features of importance consist in the utilization of a trip coil subject to one subdivision of a current in parallel with the load and a holding coil subject to another subdivision of such current in series with 35 the load, these coils being pitted against each other in operating the reclosing mechanism.

The preferred embodiment of my invention is shown in the accompanying drawings wherein similar characters of reference 40 designate corresponding parts and wherein

Figure 1 is a diagrammatic representation of my apparatus and circuits, showing the path of the current in heavy lines with the circuit normal and the circuit-breaker 45 closed.

Fig. 2 is a similar diagram showing the circuit-breaker open and the dash-pot switch falling to close a circuit in parallel with the load, and in series with a high resistance, 50 another normally closed circuit being in series with this resistance and with the load

(note, heavy line indicating the path of the current).

Fig. 3 shows the dash-pot switch closed, thus sub-dividing the current through the 55 high resistance so that it passes through a circuit in series and one in parallel with the load, the line of the series circuit and the line of the parallel circuit indicating partial diversion of the current from the series to 60 the parallel circuit as the load resistance comes back to normal.

Fig. 4 shows the load resistance back to normal and the heavy current in the parallel circuit, the trip coil having operated, and 65 the breaker being on the verge of operation.

Fig. 5 is a diagrammatic illustration of a circuit showing two methods by which I may adjust the sensitiveness of the reclosing mechanism to vary the point of operation 70 thereof.

In the drawings there is shown a generator 1, load circuit wires 2 and 3 and the load indicated at 4. In this main circuit there is a circuit-breaker 5 having leverage mechanism 6 under the control of a solenoid magnet 7. Movable with the core of this solenoid is a laterally extending arm 8, operating upon the elevation of the core of the magnet 7 to raise a switch 9. When this switch 9 is released and permitted to descend by the arm 8, such descent is retarded by dash-pot construction 10. From this description it will be seen that, when the circuit-breaker opens, the arm 8 drops and permits a gradual descent of the switch 9.

Opening of the circuit-breaker is effected by deenergization of the solenoid magnet 7, and this is brought about upon overload or short-circuit by the operation of an overload 90 switch 11 which opens a switch 12 and moves it into position to be latched open by lever 13. Thus, short-circuit or overload causes solenoid 11 and the switch 12 to deenergize the solenoid magnet 7. As a result, the circuit-breaker 5 opens and the switch 9 is free to gradually descend. During this gradual descent the motors on the circuit come to rest and the controllers or starting box levers are restored to "starting position." 95

Reclosing of the circuit-breaker will take place instantaneously upon the tripping of 100

the latch 13 and the consequent closing of the switch 12. This is insured by the spring 14 upon the switch 12. The latch 13 is tripped against restraint of spring 15 by a 5 solenoid magnet 16 under control of an index current in a manner to be described.

Figs. 1, 2, 3, and 4 represent four distinct stages of the operation. The comparative blackness of the lines in these figures indicate the current paths.

In the showing in Fig. 1 it will be noted that the conditions are normal and that the current is passing through the load and through the circuit-breaker.

15 In Fig. 2 the switch 12 has been thrown open by the overload coil 11 and is held open by the latch 13. The result is that the circuit-breaker has opened and the switch 9 has commenced falling. At this 20 time, the main circuit is, of course, broken but there is an index current passing through a high resistance 17, wire 18, holding coil 19, and wire 20 through the load. It will be noted that this holding coil 19 is in series with the load and with the high resistance 17. While the switch 9 is falling, the motors on the circuit and the controllers or starting box levers are being restored to starting position.

30 Fig. 3 shows the condition of the apparatus when the switch 9 has fallen and closed its circuit. The circuit-breaker and the switch 12 are still open and the major portion of the index current is passing through 35 high resistance 17, wire 18, holding coil 19 and wire 20 through the load. Nevertheless there is another possible path for this index current, which path is in parallel to the load. The path is indicated by lines slightly 40 less black and is through wire 21, trip coil 16, wire 23, switch 9 and wire 24. According to the representation of this figure, the load resistance is low and consequently the major portion of the index current is passing 45 through high resistance 17, wire 18, load coil 19 and wire 20 through the load, or short circuit indicated by dotted line.

Fig. 4 indicates a reversal of conditions in Fig. 3 in that the load resistance has 50 practically returned to normal by the removal of short-circuit or other overload condition and the index current, following the line of least resistance is being practically diverted through the trip coil 16. 55 (Compare the blackness of the series circuit through the coil 19 with the parallel circuit through the coil 16.)

The core of the coil 16 and the core of the coil 19 are connected by a rocking arm 60 25 and the lifting tendency of the core of the coil 16 is normally resisted by the holding tendency of the coil 19 upon its core.

In operation, it will be understood that breaking of the circuit by opening of the

switch 12 and circuit breaker 5 upon over-load or short-circuit causes the passage of an index current through the high resistance 17 and the holding coil 19 and through the load. While the switch 9 is falling and before it has closed the parallel circuit, this 65 is the only possible path for the current, and it is indicated by the heavy lines in Fig. 2. When the switch 9 has fallen, however, there is an additional path through the trip coil 16 and in parallel with the load. 70 If, however, the short circuit or overload still exists, the majority of this shunted or index current will pass through the coil 19 following the line of least resistance. Naturally the holding coil 19 tends to draw upwardly upon the rocking arm 25. As the load resistance returns to normal, the parallel circuit through trip coil 16 becomes the line of least resistance for the index 75 current and when the load resistance has about returned to normal, the trip coil 16 is about ready for operation while the holding coil 19 is sufficiently deenergized to permit its release of the rocking arm. This is the condition of the apparatus as depicted by Fig. 4 which indicates the position of the parts just before the circuit-breaker has reached closed position.

A feature of utmost importance in my improvement consists in the provision of a 95 means for varying the point of operation of the reclosing mechanism. I have conceived the idea that it is desirable to have a reclosing mechanism which may be set to close at different load resistances. Experiment and application of this idea have 100 demonstrated its extreme utility. Many cases arise in which it may be desired to change the point of operation of the reclosing mechanism. For instance, there 105 may be a number of self-starting motors connected permanently across the line, to start at 300 amperes. Addition of a number of motors or other form of load to the line might prevent the breaker from reclosing. It may be desirable to change the 110 load condition by adding more self-starting motors, lamps, etc., to the circuit. In this event, it would be very desirable to adjust the reclosing coil so that the breaker will 115 distinguish between this increased load and a short-circuit. I have provided several adjusting devices which may be utilized independently or together to effect this desired adjustment. The result is that I have obtained a much wider range of action with 120 respect to dead load resistance and have greatly increased the value of a reclosing circuit-breaker.

The preferred manner in which I render my device adjustable is shown at 26 in all the figures of the drawing. It comprises an adjustable screw 27 supported in a

bracket and so related to the core of the trip coil that adjustment of the initial position of this core may be readily effected by adjustment of the screw. Varying the initial position of the core, of course, varies the air gap and the strength of the current necessary to render the trip coil effective. In Figs. 1 to 4 inclusive, I have also shown a spring 28, adjustable by screw 29, carried upon a bracket 30. This spring is connected to the rocking arm 25 and the tensioning of it regulates the ease of operation of the trip coil.

A modified form of this portion of my invention is shown in Fig. 5 of the drawings and comprises, besides the adjusting screw 26, for the trip coil, a resistance 32. This resistance 32 is located in the series circuit through which the index current is designed to pass and is preferably adjustable. The placing of the resistance in the series circuit tends to insure the diversion of a greater portion of the index current through the parallel circuit with a result that this parallel circuit is at all times nearer to the point of operation of the trip coil. This, it will be apparent, insures a more sensitive mechanism and the adjustability or variability of the resistance results in a structure having a wider range of operation. The adjustment screw 26 or its equivalent is of vital importance in a reclosing circuit-breaker, regardless of the arrangement of the circuits and the mechanism bringing about such reclosing. The resistance 32 is also of importance for the reason pointed out, and both of these devices may be used together or independently. The form of apparatus shown in Fig. 5 is particularly desirable under certain conditions and it may be reiterated that my adjustment screw is applicable to any other circuit or mechanism, for I claim to be the first in the art to provide a means for varying the point of operation of the reclosing mechanism.

Having thus described my invention, what I claim is:

1. In a system of electrical distribution, a source of supply, a load circuit, a circuit breaker, reclosing mechanism, controlling means so related to said load circuit that it will initiate operation of said reclosing mechanism at a given load resistance, and means for adjusting the relation between said controlling means and said load circuit to render said controlling means operable at any chosen load resistance.

2. In a system of electrical distribution, a source of supply, a load circuit, a circuit breaker, reclosing mechanism, a controlling means for said reclosing mechanism, and means for adjusting said reclosing mechanism so that it will operate at any chosen load resistance.

3. In a system of electrical distribution, 65 a source of supply, a load circuit, a circuit breaker, reclosing mechanism, a controlling means for said reclosing mechanism, means for operating said reclosing mechanism at a given load resistance, and means for varying the value of load resistance at which said reclosing mechanism will operate. 70

4. In a system of electrical distribution, a source of supply, a load circuit, a circuit breaker, reclosing mechanism, an electro- 75 magnet for initiating operation of said reclosing mechanism, means for governing said electro-magnet by the load resistance, and means for adjusting said electro-magnet to make it operative at any chosen load re- 80 sistance.

5. In a system of electrical distribution, a source of supply, a load circuit, a circuit breaker, reclosing mechanism for said circuit breaker, a controlling means for said reclosing mechanism, means operative after the breaker opens to establish a sub-divided circuit, one sub-division being in series with the load and another sub-division being in parallel to the load, said controlling means 85 being in the parallel circuit and operative by the current therein, and means for varying the point of operation of said controlling means so that it may operate at any chosen load resistance. 90

6. In a system of electrical distribution, a load circuit, a circuit-breaker, reclosing mechanism, a controlling means for said reclosing mechanism, a source of supply for said reclosing mechanism, circuits for limiting and sub-dividing the current from said source and operating said controlling means thereby, and coils respectively subject to the sub-divisions of said current and pitted against each other in operation of said controlling means. 105

7. In a system of electrical distribution, a load circuit, a circuit-breaker, reclosing mechanism, a controlling means for said reclosing mechanism, a source of current 110 supply for said reclosing mechanism, circuits for limiting and sub-dividing the current from said source and operating said controlling means thereby, coils respectively subject to the sub-divisions of said current and pitted against each other in operation of said controlling means, and a rocking lever controlled by said coils in effecting such operation. 115

8. In a system of electrical distribution, 120 a load circuit, a circuit breaker, reclosing mechanism, a controlling means for said reclosing mechanism, a source of current supply for said controlling means, means for limiting the flow of current through said controlling device, a circuit whereby the load may shunt a portion of said limited current away from the controlling device, 125

and means whereby the controlling device may be adjusted to effect reclosure of breaker upon various values of load resistance.

5 9. In a system of electrical distribution, a source of supply, a load circuit, a circuit breaker, means adjustably governing the opening of said breaker under a given load

condition, and an adjustable means for controlling the reclosing of said breaker so that 10 it will reclose at any chosen value of load resistance.

In testimony whereof I hereby affix my signature.

ESTELLE C. RANEY.
